UNITED STATES PATENT OFFICE.

GRAY STAUNTON, OF NEW HAVEN, CONNECTICUT, ASSIGNOR TO VACUUM SEAL COMPANY, INC., OF NEW YORK, N. Y., A CORPORATION OF NEW YORK.

OUTSIDE-SEAL VACUUM JAR.

Application filed August 27, 1926, Serial No. 131,883. Renewed October 3, 1928.

This invention relates to vacuum sealed preserving jars.

It is an object of this invention to provide an improved form of outside sealed vacuum jars. The advantages of an outside seal lies in the smooth interior surface of the jar and in the avoidance of contamination of the contents of the jar by coming into contact with the material comprising the gasket, which in 5 an outside seal comprises only a very narrow annular ring of highly compressed material, highly impervious to the contents of the jar because of the compressed state thereof.

Other and further important objects of this 15 invention will be apparent from the disclosures in the specification and accompanying drawings.

The invention (in a preferred form) is illustrated on the drawings and hereinafter more 20 fully described.

On the drawings:

Figure 1 is an elevation of a jar partly broken away to show the features of this invention.

25 Figure 2 is an enlarged fragmentary section showing a detail of the seal.

Figure 3 is a bottom view of the cover alone.

As shown on the drawings:

A preserving jar is indicated by the number 30 10, the mouth of the jar having an external bulge or ring 11 which provides a shoulder 12 for a rubber gasket ring 13 which is initially of rectangular cross section. A cover 14 is shown having a depending circumferential flange 15, the inner surface of which has a narrow cylindrical surface 16 merging into an inwardly inclined or slanting edge or conical surface 17.

The cover is intended to be forced down 40 over the gasket ring by creating a vacuum within the jar. One means of creating such a vacuum is by the use of a hand pump having a base fitting over the cover with lugs resting on the shoulder 12 of the jar, clearance slots 45 18 being provided in the rim of the cover for these lugs. For a detailed description of a suitable pump, reference may be made to my co-pending application Serial No. 41,003, filed July 2nd, 1925. When such a pump is used, the cover serves as its own valve, rising when 50 the pump is actuated and seating at the end of the pump stroke. To give an idea of the sealing pressures available, a jar of three (3) inches diameter eighty per cent (80%) exhausted, will have an atmospheric pressure of

approximately eighty (80) pounds, a pressure ample to maintain a permanent gas tight seal. In practice, an almost perfect vacuum can be produced in the jar so that the pressure available for maintaining the seal approaches one 60 hundred (100) pounds.

With such pressures on the cover, the gasket ring, which is initially of an outside diameter fitting within the short cylindrical internal surface 16 of the cover, is compressed by 65 the conical surface 17 so that the free lower part of the gasket ring bulges out below the edge of the cover as indicated at 19 in Figure 2. This provides a cushion support for the cover and also serves to improve the seal by 70 providing a tortuous passage for any possible leakage, the sharp inner corner 20 of the cover making a very firm contact with the gasket.

To assist in opening a jar once sealed, a notch 21 is provided to permit the insertion of 75 a pin 22, or other sharp instrument, between the gasket and cover, thus allowing air to enter the jar alongside the pin to relieve the atmospheric pressure on the cover.

I am aware that numerous details of construction may be varied through a wide range without departing from the principles of this invention, and I therefore do not purpose limiting the patent granted, otherwise than 80 necessitated by the prior art.

85 I claim as my invention:

1. In a device of the class described, a vessel having an external ring below the rim thereof defining a shoulder with a cylindrical surface extending from said shoulder to said 90 rim, a resilient gasket ring positioned on said cylindrical surface, a cover for said vessel having a downwardly extending circumferential flange, a narrow cylindrical surface on the lower inside edge of said cover flange, 95 said narrow cylindrical surface being of the normal outer diameter of said gasket ring, and an inwardly tapering conical surface merging with the cylindrical surface and the lower surface of the cover, whereby forcing 100 said cover down over the vessel by creating a vacuum therein will compress said gasket ring by means of said conical surface and cause said gasket to bulge outwardly below the lower edge of the cover.

105 2. In combination, a jar having a peripheral flange defining a shoulder beneath the rim thereof, a resilient gasket of initially rectangular cross section positioned above said shoulder, a cover for said jar adapted to act 110

as a valve while creating a vacuum within its rim shouldered to form a seat for a gasket, a peripheral depending flange on said cover having an inner cylindrical lower surface of approximately the same diameter as the initial outer diameter of the gasket, said surface merging into an inwardly tapering upper surface adapted to compress the gasket on said jar whereby said gasket is adapted to be forced outwardly beneath the lower edge of said cover.

3. In combination, in a vacuum jar construction with an outside seal of the class described, a container having the outer edge of its rim shouldered to form a seat for a gasket, 15 a gasket resting on said seat, and a cover normally disposed out of contact with the container when sealed thereto for cooperation with said gasket and arranged to serve as a valve during the sealing of the container,

20 said gasket when compressed bulging between the lower and cooperating edge of the cover and the shouldered edge of the container.

4. In combination, in a vacuum jar construction with an outside seal of the class described, 25 a container shouldered to form a seat for a gasket, a gasket resting on said seat, and a cover normally disposed out of contact with the container when sealed thereto for cooperation with said gasket having a slanting 30 internal edge, said edge being positioned in a slanting plane between the horizontal and vertical so as to wedge the gasket on its seat and cause the gasket to bulge under the lower edge of the cover and over the shoulder on 35 said jar.

5. In combination, in a vacuum jar construction, with an outside seal of the class described, a container having the outer edge of

40 a gasket resting on said seat, and a cover normally disposed out of contact with the container when sealed thereto for cooperation for said gasket and arranged to serve as a valve during the sealing of the container, 45 said gasket when compressed bulging between the lower and cooperating edge of the cover and the shouldered edge of the container, said cover having a flange with an edge disposed in a plane between the horizontal and vertical for engaging and compressing the gasket upon its seat, the flange being provided with a slot arranged for an instrument to be inserted therein and in substantial alignment with said last mentioned edge, whereby the seal may be broken between this edge and the gasket. 50

6. In combination, in a vacuum jar construction with an outside seal of the class described, 55 a container having the outer edge of its rim shouldered to form a seat for a gasket, a gasket resting on said seat, and a cover normally disposed out of contact with the container when sealed thereto for cooperation with said gasket and arranged to serve as a valve during the sealing of the container, 60 said gasket when compressed bulging between the lower and cooperating edge of the cover and the shouldered edge of the container, said cover having a flange with an edge disposed in a plane between the horizontal and vertical for engaging and compressing the gasket upon its seat. 65

In testimony whereof I have hereunto subscribed my name.

GRAY STAUNTON.
